UNITED STATES PATENT OFFICE.

ROBERT LE FORT, OF PHILADELPHIA, PENNSYLVANIA, ASSIGNOR TO
POLLITZ, KAUFMAN & CO., OF SAME PLACE.

FABRIC-TRIMMING MACHINE.

SPECIFICATION forming part of Letters Patent No. 632,314, dated September 5, 1899.

Application filed May 12, 1899. Serial No. 716,474. (No model.)

To all whom it may concern:

Be it known that I, ROBERT LE FORT, a citizen of the United States, residing in the city and county of Philadelphia, State of Pennsylvania, have invented a new and useful Improvement in Fabric-Trimming Machines, which improvement is fully set forth in the following specification and accompanying drawings.

My invention consists of an implement adapted for trimming a fabric, more particularly that around the designs of "applique," the same embodying a movable blade, a foot which is adapted to pass under and raise the facing goods and constitutes in part a bed-knife, and means for imparting motion to said blade, as will be hereinafter described.

Figure 1 represents a partial side elevation and partial vertical section of a trimmer embodying my invention. Fig. 2 represents a side elevation thereof. Figs. 3 to 11, inclusive, represent detail views thereof.

Similar letters of reference indicate corresponding parts in the figures.

Referring to the drawings, A designates a frame in which is mounted the vertically-arranged shaft B, to which is attached the flexible shaft C, by which power of a motor may be communicated to said shaft B to rotate the same.

On the lower end of the shaft B is the head D, on which is the eccentrically-arranged wrist-pin E, which freely enters a slot in the slide F, which latter is mounted on the limb G of the rocking stock H, whose axis is on the supporting base or shoe J of the casing A.

K designates a blade which is connected with the lower limb of the stock H and adapted to receive motion in opposite directions by the latter.

Connected with the base J is the forwardly-projecting foot L, which is below the blade K and has a cutting edge M, thus providing a bed-knife for the blade K. In order to adjust said blade, the stock is provided with the curved slot N, which receives the screw P, the latter entering the blade K, so that the latter

may be properly set and secured in position, it being evident that the blade and bed-knife may be removed for sharpening, repairs, &c. 50

The operation is as follows: Power is transmitted to the shaft B, whereby the stock H, owing to the intermediate parts, receives rocking or reciprocating motions, and the blade K is accordingly raised and lowered. The foot 55 L is passed under the facing goods a, and the latter is raised from the backing b and subjected to the shearing action of the blade and bed-knife, and thereby cut or trimmed, the implement being moved along by hand and 60 guided around the designs, borders, &c., of the fabric and sustained on the shoe J.

Having thus described my invention, what I claim as new, and desire to secure by Letters Patent, is—

1. A trimming implement consisting of a blade, a bed-knife, means for operating said blade, a support for said parts, and a lifting-foot attached to said bed-knife said means consisting of a rocking stock, a slide in said 70 stock, and a shaft, with a wrist-pin, the latter freely entering said slide.

2. A blade, a bed-knife, a rocking stock, connected with said blade, a slide in said stock, an operating-shaft having a wrist-pin which 75 freely enters said stock an elevating-foot attached to said bed-knife, a support for said members and a flexible shaft connected with said operating-shaft, the parts named being combined forming a hand implement for trimming fabric. 80

3. In a trimming implement a blade, a bed-knife and elevating-foot below said blade, a stock to one limb of which said blade is attached, means for rocking said stock consisting of a slide on said stock, and a wrist-pin on said shaft freely entering said slide and a support for said parts, said blade and stock being adjustably connected by means of a slot and screw on the respective members. 85

ROBERT LE FORT.

JOS. KAUFMAN.

Correction in Letters Patent No. 632,314.

It is hereby certified that the name of the patentee in Letters Patent No. 632,314, granted September 5, 1899, for an improvement in "Fabric-Trimming Machines," was erroneously written and printed "Robert Le Fort," whereas said name should have been written and printed *Robert Le fort*; and that the said Letters Patent should be read with this correction therein that the same may conform to the record of the case in the Patent Office.

Signed, countersigned, and sealed this 12th day of September, A. D., 1899.

[SEAL.]

WEBSTER DAVIS,
Assistant Secretary of the Interior.

Countersigned:

C. H. DUELL,
Commissioner of Patents.
